UNITED STATES PATENT OFFICE.

HIPPOLYTE BERGERON, OF LONGUE POINTE, CANADA.

MEANS FOR UTILIZING SPACE IN CROWDED MUNICIPALITIES.

SPECIFICATION forming part of Letters Patent No. 671,686, dated April 9, 1901.

Application filed September 4, 1900. Serial No. 28,967. (No model.)

To all whom it may concern:

Be it known that I, HIPPOLYTE BERGERON, a subject of Her Majesty the Queen of Great Britain, residing at Longue Pointe, county of 5 Laval, Province of Quebec, Canada, have invented certain new and useful Improvements in Means for Utilizing Space in Crowded Municipalities; and I do hereby declare that the following is a full, clear, and exact description of the invention, such as will enable others skilled in the art to which it appertains to make and use the same.

My invention is a means for utilizing space in crowded municipalities by making provision for the erection of an elevated business-building, such as an office-building or a department-store, as well as for an elevated railway, (electric or other mechanically propelled,) besides securing in a substantial foundation 10 and below the grade of an ordinary street the several conduits required for burying underground the necessary water and gas mains, the telephone and telegraphic wires, and the cables or heavy conductors required for the 15 transmission of electric energy for light and power purposes. The foundation also accommodates a sewer by which waste sewage-water may be carried off, and in a tunnel adjacent to the sewer may operate cars or vehicles for 20 transporting solid sewage matter cleaned from the sewer. Access to the foot-platforms of the elevated railway is attained by spiral or other stairways that wind around columns for 25 the support of the overhead business structure, and these stairways, as well as inclined roadways or footwalks, also lead to an elevated roadway or roadways adjacent to the 30 business structure.

The invention consists in the novel construction and arrangement of parts which will be hereinafter fully described and claimed.

In the accompanying drawings, forming a part of this specification, Figure 1 is a view in elevation of the elevated building with the 40 stairways and the road approaches thereto, showing the invention erected on a boulevard between two rows of houses or buildings and also illustrating the foundation in section. Fig. 2 is a sectional elevation, on an enlarged 45 scale, of the lower part of the structure shown by Fig. 1, the elevated building and the road approaches thereto being broken away. Fig.

3 is a sectional elevation, on an enlarged scale, in the plane of the dotted line 3 3 on Fig. 4. Fig. 4 is a sectional plan view in the plane of 55 the dotted line 4 4 on Fig. 3.

The same numerals of reference denote corresponding parts in the several figures of the drawings.

The system for saving space contemplated 60 by this application is especially designed for installation in a wide avenue or boulevard of a city or other municipality where space is valuable, and in carrying the invention into practice I first proceed to make an excavation, as at 10, in the ground below the street-grade 11. In this excavation is placed the concrete or artificial-stone foundation 12, which may, however, be of any other material than the particular material herein mentioned. This artificial foundation is molded and fashioned to produce therein a tunnel 13, a sewer 14, and one or more conduits 15 16, two of said conduits being shown by the drawings and as being located on opposite sides 70 of the tunnel. The conduits and the tunnels are at proper intervals, so as to provide for the erection on the foundation of a plurality of columns 17 17^a, designed for the support of the overhead girders 18, the latter being 75 arranged longitudinally and transversely of the business structure 20. The columns 17 17^a are preferably of metal constructed in a way approved by the skilled constructor to sustain great strain, and they rise a suitable 80 height above the street-grade 11, whereby the elevated building may be placed high enough above the street-grade to accommodate the means for supporting an overhead railway. The transverse girders 18 extend for proper 85 distances beyond the sides of the business structure 20, so as to afford the support for the footwalks or sidewalks 21 of the elevated roadways 22, said extended or prolonged ends of the transverse girders being stayed by the 90 inclined struts 19, the latter being preferably secured at their lower ends to the columns, so as to terminate above grade. The business structure may be adapted for any suitable business, such as an office-building or 95 for manufacturing purposes, and it is evident that said building may be erected of iron, stone, brick, or any other materials selected and approved by the skilled construc- 100

tor. Access to the elevated structure may be obtained by carriages through the medium of the inclined roadways or approaches 23, which may extend into the cross or intersecting street, so as to give a gradual ascent to the elevated roadways 22, and, as will hereinafter appear, access by stairways is also attained to said elevated structure.

Between the columns (indicated by the number 17^a in Fig. 2) I secure a series of transverse track-girders 24, and the platform-girders 25 are between the two pairs of columns 17 17^a, respectively, said platform-girders being disposed in series on opposite sides of the elevated tracks 26, which accommodate the cars of an elevated railway, as indicated by Figs. 1 and 2, it being evident that the cars in said elevated railway may be propelled by electric energy or any other motive power. The platform-girders 25 sustain the platforms 27, adapted to accommodate the traveling public in attaining access to the cars of the elevated railway. The spiral stairways 28, any desired number of which may be employed, are erected around the columns 17, so as to have a landing on each elevated platform 27 and the elevated side or foot walk 21. The sewage matter from the buildings adjacent to my improved system is discharged by the drains 29 into the sewer 14, which is formed centrally in the artificial foundation. The sewer may be lined with a masonry wall which is arched to have its end portions 30 extended above the road-beds 31, which are provided in the tunnel on opposite sides of the sewer, and on these road-beds are laid the tracks 32. The track on one side of the tunnel accommodates a car 33, which is equipped with a crane 34, adapted to suspend an excavating appliance operatively over the sewer for the purpose of cleaning the latter by removing solid matter therefrom. The other track 32 on the opposite side of the sewer accommodates a car 35, into which the excavator operated by a crane may discharge its load, said car adapted to be hauled by suitable motive power through the tunnel. The tunnel 13 is of larger cross-sectional area than either of the conduits 15 16, and access and communication between the tunnel and these conduits is attained by the provision of a doorway 36 between each conduit and the tunnel. One of such doorways 36 is shown by Fig. 3, and in which is a stairway 37 to enable a workman to pass from the floor of the tunnel up to the floor of the conduit. Each conduit accommodates a water-supply pipe 38, from which branch pipes may lead to any number of places to be supplied with water from the city mains. A series of cross-beams 39 are embedded in the walls of the conduit to support one or more gas-supply mains 40, from which mains may lead a proper number of pipes to convey gas to the lamps designed for the illumination of the buildings or streets.

A series of girders 41 span the tunnel 13,

and other girders 42 span the conduits 15 16, said girders adapted for the purpose of a bridge, which is flush with the street 11 at 70 grade, thus making provision for the passage of street traffic beneath the elevated structure and the elevated railway. The tunnel 13 also accommodates the means for supporting telephone, telegraph, and electric conductors 75 adapted to transmit energy required for lighting and power purposes. Two series of posts 43 are provided in the tunnel on opposite sides of the sewer, and on these posts are secured the I-beams 44. At proper intervals 80 these I-beams are intersected by the cross-beams 45 46, the cross-beams 46 being elevated above the beams 45, which latter extend entirely across the tunnel. The cross-beams between the two series of posts support the track 47 and the platform 48, whereby a repair-car may travel on the track and the attendant workmen are enabled to work on the platform in installing or repairing the electric wires. The bars 49, with the insulators 50, are supported on the beams 45 46 to afford a number of points of attachment for the wires. It will be noted that the wires or conductors are contained in the tunnel below the grade of the street, and access is 95 readily obtainable to these conductors for the purpose of repairing the same.

Changes within the scope of the appended claims may be made in the form and proportion of some of the parts, while their essential features are retained and the spirit of the invention is embodied. Hence I do not desire to be limited to the precise form of all the parts as shown, reserving the right to vary therefrom.

Having thus described my invention, what I claim as new is—

1. A structure of the character described, comprising an artificial foundation, the columns erected on the foundation, a building supported above grade by the columns, the elevated sidewalks and roadways upheld by the columns and disposed on opposite sides of the building, and an elevated-railway track mounted on the two columns between the building and the street-grade, substantially as described.

2. A structure of the character set forth, comprising a foundation having a tunnel and a conduit, the columns erected on said foundation, the girders supported by the columns and provided with the sidewalks and the roadways on opposite sides of an elevated building, the inclined approaches to said roadway, a railway track and platform supported by the columns between the street at grade and the elevated building, and stairways having landings at the platforms and at the sidewalks, substantially as described.

3. A structure of the character set forth, comprising a foundation, the columns, an elevated building upheld by the columns above the street-grade, a railway track and platforms between the street at grade and the elevated

- building, the roadways and sidewalks supported by the columns on the level of the elevated building, and stairways or approaches affording communication to the platforms, 5 the elevated building and the roadways from the street at grade, substantially as set forth.
4. A structure of the character described, comprising a foundation below the street-grade and having a central tunnel and a sewer, 10 road-beds in the tunnel and at opposite sides of the sewer, and adapted for the transit of repair and cleaning cars, electric conductors strung within the tunnel and over the road-beds, substantially as described.
- 15 5. A structure of the character described, having a foundation below the street-grade and provided with a tunnel, a sewer in communication therewith, the road-beds in the tunnel and on opposite sides of the sewer, and 20 adapted for the transit of repair and cleaning cars, the subways on opposite sides of the road-beds, and the electric conductors strung in the tunnel and over the road-beds, substantially as described.
- 25 6. A structure of the character described, comprising a foundation below the street-grade and having a central tunnel, a sewer, the conduits at opposite sides of the tunnel and in communication therewith through an 30 intermediate doorway, a plurality of supply-mains in the conduits, railway-tracks situated in the tunnel and between the sewer and the conduits, and adapted for the transit of repair and cleaning cars, the electric conductor-supports overhanging the tracks, substantially as described.
- 35 7. A structure of the character set forth having a tunnel and a sewer, posts erected in the tunnel on opposite sides of the sewer, transverse beams mounted on the posts and 40 spanning the sewer, insulators for electric wires on said beams, and a track also supported on the beams and disposed between the two series of insulators and in the vertical plane of the sewer, said track adapted to support a repair-car, substantially as described. 45
8. A structure of the character set forth, having a foundation provided with a tunnel, and the road-beds, a sewer centrally disposed to the tunnel and arranged between the road-beds, the posts erected in the tunnel on opposite sides of the sewer, the cross-beams supported by the posts and extending over the road-beds, the insulated supports on the beams, and a track and platform mounted on 50 the beams over the sewer, substantially as described. 55
9. A structure of the character set forth comprising a foundation having below grade a tunnel, a sewer, conduits on opposite sides 60 of the tunnel and communicating therewith through suitable doorways, the posts in the tunnel and on opposite sides of the sewer, the transverse beams on the posts, a track, and the insulators supported by the beams within 65 the tunnel, the girders spanning the tunnel above the track, other girders over the conduits, and a floor on the girders and flush with the street at grade, substantially as described.

In witness whereof I have hereunto set my 70 hand in the presence of two witnesses.

HIPPOLYTE BERGERON.
